UNITED STATES PATENT OFFICE

EDWIN G. LITTLE, OF WILKINSBURG, PENNSYLVANIA, ASSIGNOR TO THE UNION SWITCH & SIGNAL COMPANY, OF SWISSVALE, PENNSYLVANIA, A CORPORATION OF PENNSYLVANIA

RAILWAY-SWITCH-LEVER LOCK STAND

Application filed June 3, 1929. Serial No. 367,873.

My invention relates to railway switch lever lock stands, and particularly to lock stands wherein the usual throwing lever for manually operating a railway switch or the selector lever of a dual control mechanism is held against movement by a pivoted locking member when and only when a locking device such as a padlock is applied to the locking member.

10 One object of my invention is the construction of the locking member in such manner that the locking member is automatically moved to the position for receiving the locking device upon the insertion of the lever into the lock stand, and is automatically moved away from this position when the lever is withdrawn.

I will describe one form of lock stand embodying my invention, and will then point 20 out the novel features thereof in claims.

In the accompanying drawing, Fig. 1 is a vertical sectional view showing one form of lock stand embodying my invention, a lever 6 being shown in place in the lock stand. 25 Fig. 2 is a top plan view of the base 1 of the lock stand shown in Fig. 1. Fig. 3 is a side view of the jaw 2 and locking member 7 shown in Fig. 1 as they appear when viewed from the right in Fig. 1.

30 Similar reference characters refer to similar parts in all three views.

Referring to the drawings, the lock stand, in the form here shown, comprises a jaw 2 pivotally attached to a base 1. The base 1 comprises a semi-circular lower portion 1^a and an integral pedestal 1^b. The lower portion 1^a is provided with holes 1^c whereby the base may be secured to a railway tie or other suitable foundation not herein shown.

40 The jaw 2 may be pivotally attached to the base 1 in any suitable manner. As here shown, a pin 3 is journaled in a hole 1^d in the pedestal 1^b, and extends upwardly into an opening 2^a in the lower part of the jaw 2.

45 The pin 3 is secured to the jaw 2 by means of a rivet 4, and is held in the base 1 by a head 3^a. A set screw 9, extending through the side of the pedestal 1^b into the hole 1^d, as clearly shown in Fig. 2, is adapted to be screwed into 50 engagement with the pin 3 to prevent move-

ment between the base and the jaw when the jaw has been turned to the desired position with respect to the base.

The upper part of the jaw 2 is provided with a recess 2^e adapted to receive the throwing lever 6 or the selector lever of a railway switch not shown. The jaw 2 also has formed therein a vertical slot 2^b (Fig. 3) which extends through the jaw at right angle to the plane in which the lever 6 rotates. 55 Mounted to oscillate within the slot 2^b on a pin 8 carried by the jaw 2, and biased by its own weight to the normal position shown, is a locking member 7 comprising two arms 7^a and 7^b, one of which extends upwardly 60 on each side of the recess 2^e (see Figs. 1 and 3). The arm 7^a is provided, at its upper end, with a latch 7^d, the upper and lower faces of which are shaped as shown, and which latch normally projects into the 65 recess 2^e in the path of movement of the lever 6 into or out of said recess. The arm 7^b is provided at its upper end, with an eye 7^c, which is normally located just outside of the slot 2^b, and through which a padlock or other 70 suitable locking device may be passed when it is desired to prevent the removal of lever 6 from the recess 2^e. A stop 7^f, formed on the lower part of the arm 7^b, engages the jaw 2 at the bottom of the slot 2^b to limit the 75 counter-clockwise rotation of the locking member 7, while a flat surface 7^g on the upper end of the arm 7^b is adapted to engage the jaw 2 at face 2^d to limit the clockwise rotation of the locking member 7.

80 The operation of the lock stand is as follows: When the parts occupy the positions in which they are illustrated in the drawing, that is, with the latch 7^d of the locking member 7 overlying the throwing lever 6, and with the eye 7^c exposed, if a locking device such as a padlock is placed in the eye 7^c, rotation of the locking member 7 is prevented, and the lever 6 is therefore held in the recess 2^e of the jaw 2 by the latch 7^d. If the eye 7^c is unoccupied by a locking device, under the above conditions, however, the locking member 7 is free to rotate, and due to the 85 shape of the lower face of the latch 7^d and to the location of the point at which the locking 90 member 7 is pivoted, the lever 6 is held in the slot 2^b of the jaw 2 by the stop 7^f. If the eye 7^c is occupied by a locking device, the locking member 7 is free to rotate, and due to the shape of the lower face of the latch 7^d and to the location of the point at which the locking 95 member 7 is pivoted, the lever 6 is held in the slot 2^b of the jaw 2 by the stop 7^f. If the eye 7^c is occupied by a locking device, the locking member 7 is free to rotate, and due to the shape of the lower face of the latch 7^d and to the location of the point at which the locking 100 member 7 is pivoted, the lever 6 is held in the slot 2^b of the jaw 2 by the stop 7^f.

member is pivoted, if the lever 6 is then moved upwardly in the recess 2^c, the lever, upon striking the latch 7^a, will automatically move the locking member to a position in which the latch is out of the path of movement of the lever and the eye 7^c is within the slot 2^b. When the lever has passed the latch, the locking member will normally drop back to the position shown under the influence of gravity. If the lever is then again inserted in the recess 2^c, the lever upon entering the recess will strike the latch 7^a upon its upper curved face and will rotate the locking member to a position in which the latch 7^a is out of the path of movement of the lever and the eye 7^c is within the slot 2^b until after the lever has passed the latch, whereupon, the locking member will normally return to its normal position under the influence of gravity. If the locking member should stick in the position in which the latch 7^a is out of the path of movement of the lever 6 and the eye 7^c is within the slot 2^b due for example to friction between the locking member and the pin 8, the surface 7^e of the locking member 7 between the arms 7^a and 7^b would be raised above the bottom of the recess 2^c and if the lever is then inserted in the recess, the lever will engage the surface 7^e before the lever reaches the bottom of the recess and the lever will force the locking member back to its normal position in which the latch 7^a overlies the lever and the eye 7^c is exposed to receive a locking device.

It should be pointed out that due to the proportioning of the parts, when the lever is locked in the stand by a padlock or other locking device being inserted in the eye 7^c, only a small fraction of any force applied to the lever to remove the lever from the recess is transmitted as a shearing force on the padlock.

One advantage of a lock stand embodying my invention is that the throwing lever is securely held in place in the stand upon the application of a locking device to the locking member, but that the throwing lever is automatically released upon the removal of the locking device from the locking member.

Another advantage of a lock stand embodying my invention is that since the jaw is pivoted on the base 1, and since the vertical axis of the jaw is near the edge of the base, the stand may be attached to a tie with the axis of the jaw close to the edge of the tie or at an intermediate point on the tie as conditions may require.

Although I have herein shown and described only one form of lock stand embodying my invention, it is understood that various changes and modifications may be made therein within the scope of the appended claims without departing from the spirit and scope of my invention.

Having thus described my invention, what I claim is:

1. The combination with a movable lever for controlling a railway switch, of a jaw having a recess adapted to receive said lever, a locking member comprising two upwardly extending arms one of which is provided with an eye and the other of which is provided with a latch, means for pivotally attaching said locking member to said jaw in such manner that said member is biased to a position in which said latch extends into the path of movement of said lever into or out of said recess and said eye is exposed, the parts being so proportioned that when said lever is entering said recess said lever engages said latch in a manner to automatically move said locking member to a position in which said latch is out of the path of movement of said lever and access to said eye is prevented but that when said lever has completely entered said slot said lever engages said locking member between said arms and positively moves said locking member to the position to which said member is biased.

2. The combination with a movable lever for controlling a railway switch, of a jaw having a recess adapted to receive said lever and having a vertical slot extending through said jaw at right angles to the plane in which said lever moves, a locking member located in said slot and pivoted to said jaw and comprising two upwardly extending arms, one of which is provided with a hole normally located outside of said slot and the other of which is provided with a latch normally extending into said recess in the path of movement of said lever, the pivot of said member and said latch being so arranged with respect to said lever that said lever in its downward movement will act upon said latch and rotate said locking member to a position in which said latch is out of the path of movement of said lever and said eye is in said slot, and said locking member also having a part between said arms arranged to move into the path of movement of said arm when said latch is moved out of said path for returning said lever to the position in which said eye is out of said slot and said latch is in the path of movement of said lever after said lever has completely entered said recess.

3. The combination with a movable lever for controlling a railway switch, of a base having a semi-circular lower portion provided with holes for attaching the base to a suitable foundation and having an integral pedestal provided with a hole, a jaw having a recess in its upper surface for receiving said lever and an opening in its lower surface and also having a vertical slot extending therethrough at right angles to the plane in which said lever moves, a pin extending through the hole in said pedestal into said opening in said jaw and riveted to said jaw and held in said pedestal by a head, a set screw in said pedestal for engaging said pin

to prevent movement of said jaw with respect to said base, a locking member located in said slot and pivoted to said jaw and comprising two upwardly extending arms, one of which is provided with a hole normally located outside of said slot and the other of which is provided with a latch normally extending into said recess in the path of movement of said lever, said latch and the pivot of said member being so arranged with respect to said lever that said lever in its downward movement will act upon said latch and rotate said locking member to a position in which said latch is out of the path of movement of said lever and said eye is in said slot, and said locking member also having a part between said arms arranged to move into the path of movement of said arm when said latch is moved out of said path for returning said lever to the position in which said eye is out of said slot and said latch is in the path of movement of said lever after said lever has completely entered said recess.

In testimony whereof I affix my signature.

EDWIN G. LITTLE.
